Des. 208,889
Patented Oct. 10, 1967

208,889

TAPE DISPENSER

Robert B. Baeker, Newtown, Conn., assignor to Minnesota Mining and Manufacturing Company, St. Paul, Minn., a corporation of Delaware

Filed May 17, 1966, Ser. No. 2,332

Term of patent 14 years

(Cl. D74—1)

FIG. 1

FIG. 2

FIGURE 1 is a top, front and left side perspective view of a tape dispenser showing my new design; and

FIGURE 2 is a top, front and right side perspective view thereof.

The back of the design is plain and unornamented.

I claim:

The ornamental design for a tape dispenser, substantially as shown and described.
